UNITED STATES PATENT OFFICE

2,129,492

SHOE

Arthur O. Dahlberg, Washington, D. C.

Application July 5, 1935, Serial No. 29,799

12 Claims. (Cl. 36—8.5)

My invention relates generally to shoes, and more particularly to an improvement in the construction of shoes whereby the shoe will maintain its shape when not being worn.

5 It is a well known fact that shoes after having been worn for a short time, tend to lose their shape, particularly due to the fact that the sole warps, causing the toe portion of the shoe to turn upwardly. This tendency is very pronounced in ladies' shoes. To overcome this tendency it is, of course, the common practice to insert shoe trees or shoe stretchers into the shoes while they are not being worn. The insertion of the shoe trees is, however, a bothersome task.

10 Furthermore, some shoes being of lighter construction than others, require a shoe tree having a much lighter spring than is required for shoe trees to be used in shoes of more substantial construction. Thus, it requires a relatively large assortment of shoe trees in order properly to preserve the shape of the particular types of shoes which a person may have at a particular time.

15 It is an object of my invention to provide an improved shoe having incorporated therein a resilient member which will perform the functions of a shoe tree when the shoe is not being worn and will not interfere with the comfort of the shoe while it is being worn.

20 A further object is to provide an improved shoe having a resilient strip of metal arcuate in cross section structurally incorporated in the sole thereof.

25 A further object is to provide an improved shoe having a resilient element incorporated in the sole thereof and arranged to hold the shoe in properly stretched shape while it is not being worn.

30 Other objects will appear from the following description, reference being had to the accompanying drawings, in which:

Fig. 1 is a side elevation of a shoe incorporating my invention;

Fig. 2 is a sectional view of the shoe taken on the line directly above the sole, a portion of the insole and sock lining being broken away to show the resilient member;

Fig. 3 is a perspective view of the resilient member;

Fig. 4 is a view similar to Fig. 2 showing a modified form of my invention in which two resilient members are incorporated in the shoe;

Fig. 5 is a transverse sectional view of the toe portion of a shoe;

Fig. 6 is a similar view illustrating a modified

method of incorporating the resilient member in the sole of the shoe;

Fig. 7 is a transverse sectional view taken on the line 7—7 of Fig. 8;

Fig. 8 is a sectional view taken directly above 5 the insole of a shoe incorporating a modified form of my invention, portions of the insole being shown as broken away to illustrate the internal construction;

Fig. 9 is an elevation of a shoe incorporating 10 my invention in the shape assumed while it is being worn;

Fig. 10 is a view similar to Fig. 9 showing the shoe in the shape assumed while it is not being worn and has been flexed downwardly; 15

Fig. 11 is a side view of a shoe incorporating a further modified form of my invention;

Fig. 12 is a side view of the resilient member utilized in the shoe shown in Fig. 11;

Fig. 13 is an enlarged end view of the 20 resilient member shown in Fig. 12; and

Fig. 14 is an enlarged transverse sectional view of a modified form of resilient member, similar to that shown in Figs. 12 and 13, but with a covering applied thereto. 25

The salient feature of my invention is the incorporation in the sole or insole of a shoe, of a resilient member which tends to flatten the sole of the shoe, and one that does so decisively, at the election of the owner, when the shoe is not 30 being worn, thereby maintaining the shoe in shape. The preferred form of resilient member is a strip of thin, high tensile strength steel, preferably stainless, which is arcuate in cross section. A familiar example of the type of resilient member used is the self-supporting flexible steel scale, of the type disclosed in the patent to Farrand, No. 1,402,589. This type of resilient member has the pronounced advantage that it possesses considerable rigidity (especially with 35 respect to bending toward its convex surface) when straight, but is very easily flexed after a critical point in its flexure has been passed.

It will be noted in Fig. 1 that the shoe comprises a counter 10 having a strap 12 and a 45 combined toe and vamp 14, shank 16, and outsole 18. In this figure, the shoe is shown in full lines in the position in which it is held by the resilient member, and in dotted lines in the shape the shoe assumes when flexed as when being 50 worn while walking. The dotted lines also illustrate the conformation the shoe would assume when not being worn if my invention were not incorporated therein.

The resilient member 20 comprises a strip 22 55

which is arcuate in cross section and which is preferably made of a high tensile strength steel. It is preferably a rust proof or stainless steel and is sufficiently thin so that when it is flexed (especially toward its convex surface) beyond the position at which it assumes a shape lineal in transverse cross section, it is so flexible that its presence will not be noticeable to the wearer. An ordinary self-supporting steel tape of the type disclosed in the above noted Farrand patent is of approximately the shape, size and kind of material required. Of course, for different shoes the dimensions and the material used will be varied. For example, for mens' shoes having a heavier outsole than the shoe illustrated in Fig. 1, the resilient strip will, of course, be made heavier or wider, or both.

The strip 22 preferably has a plurality of projecting lugs 24 stamped therefrom to aid in anchoring the strip in the insole of the shoe. In Fig. 3, the strip 22 is illustrated as having a coating or covering 26 of rubber or other suitable material for protecting the strip against corrosion and oxidation, and to render it less liable to cut into the sole in which it is embedded.

As best shown in Figs. 2 and 5, the insole 28 has a slot 30 formed therein to receive the strip 22. The lugs 24 on the strip 22 project into the soft material of the insole 28 or into the lining sole 32, depending upon the depth of the slot 30, and thus hold the strip against movement relative to the insole. The insole may be made of sheet cork or other suitable material and it is preferably covered by a thin leather, cloth, or composition lining sole 32. The resilient member 22 preferably extends along a line indicated at 34 in Fig. 2 and passing from the center of the heel portion through the approximate center of pressure of the ball of the foot upon the sole, although considerable variation from this location is feasible. In this form of my invention the strip 22 extends only a short distance beyond the ball of the shoe but extends a sufficient distance into the shank portion to form an anchorage in the shank for the strip. The strip may be cemented, sewed, cleated by means of lugs such as indicated at 24, or otherwise secured in place, but it is desirable to secure the strip so firmly in place that there will be no danger that it may work itself loose.

In the act of putting on the shoe, the strip 22 will flex upwardly at one point or at a given transverse line, in a manner to permit the sole to flex and remain flexed in the vicinity of such point as long as the shoe is being worn. The location of the point or transverse line at which the strip will flex will, of course, depend upon the character of the shoe and the characteristics of the foot of the wearer, but generally speaking, will be located at the point of maximum flexure of the sole. At this point of flexure the strip has very little resistance to bending movement so that the presence of the strip will not be noticeable to the wearer. When the shoe is removed, this point of flexure (where the strip is of lineal transverse cross section) will usually remain due to the inherent tendency of the sole to turn up. However, a slight downward flexure of the toe of the shoe relative to the heel will readily cause the strip 22 to resume its transverse arcuate cross section throughout its length, and when in this shape the strip is sufficiently rigid to maintain the toe of the sole depressed. This straightening of the sole of the shoe will cause the vamp and toe cap piece of the shoe to maintain their prop-

er shapes. It will be understood that during the act of walking, the transverse line of flexure of the strip 22 may shift back and forth to a certain extent as the curvature of the sole changes with successive shifting of the weight of the wearer from the heel toward the toe. This shifting of the transverse line of flexure takes place under the influence of relatively small forces, and thus the strip does not noticeably add to the stiffness of the sole of the shoe while the shoe is being worn. When, however, the shoe is removed from the foot and the strip 22 straightened by bending the toe portion of the sole downwardly the sole is stiffened by the metallic strip 22, and thus holds the shoe in shape as above described.

In Fig. 4 I have shown a modified form of shoe in which two strips 22 are incorporated in the same manner as the single strip shown in Figs. 2 and 5. When a shoe having a relatively heavy and rigid sole is to be equipped with my invention, two or more strips may be used, as shown in Fig. 4. If desired, however, two strips may be used for relatively light weight soles, in which case the strips will be of thinner metal, or will be narrower, or both.

In Fig. 6 I have illustrated a modified form of my invention in which the strip 36 is positioned in a rubber insole 38. The rubber is preferably bonded directly to the strip 36. This construction has the advantage that the danger of the metallic strip working loose and being a source of discomfort to the wearer is substantially eliminated. The rubber insole 38 may be vulcanized, cemented, or sewed to the outsole 18 which may be of rubber, or the insole 38 and outsole 18 may be integral.

In Figs. 7 and 8 the strip is mounted in the same manner as shown in Figs. 2, 3, and 5, but a weight distributing flexible member 48 is located between several plies of the lining insole 50, or may be located between the lining insole and the insole proper 28. This weight distributing member 48 may be in the form of a very thin sheet of metal, in the form of a metallic wire screen, or in the form of a heavy stiff cloth or other suitable material. The member 48 not only aids in preventing the strip 22 from wearing through the lining insole, but also reduces the possibility of discomfort to the wearer, since the pressure of the strip 22 upon the foot, which might otherwise be exerted upon a limited area of the foot, is distributed over a larger area.

Fig. 10 shows a shoe incorporating a slightly modified form of my invention, in which the metallic strip 52 is slightly convex (upwardly) instead of being rectilinear in longitudinal cross section. It will be noted from Fig. 10 that this strip will snap into its relatively rigid position when the toe portion of the shoe is bent downwardly beyond its normal position, and thus tends to exert a greater force to hold the sole of the shoe in a flat or plane position.

The strip 52, as shown in Figs. 12 and 13, is otherwise of substantially the same construction as the strip 22 previously described. It may, however, as indicated in Fig. 14, be covered with a thin layer 54 of rubber or other suitable material.

The shoe shown in Fig. 11 has a strip such as shown in Fig. 12 incorporated therein, and the position assumed by the strip 52 while the shoe is being used in walking is indicated by the dotted line 56, while the shape which the strip 52 would assume if free is indicated by the dotted line 58. The shape of the shoe indicated in full lines in

Fig. 11 is that assumed by it when the shoe is not being worn, in which instance the strip 52 is flexed slightly throughout its length but the strains imposed on the strip at no point reach the critical value at which the strip will snap into the shape where it has a pronounced bend at one point. The strip will maintain its transverse arcuate shape throughout the entire length under these conditions. In other respects the modified form of my invention shown in Figs. 11 to 13, inclusive, may be substantially the same as any one of the constructions previously described.

It will be noted, however, that the strip need not extend into the shank. Whether the strip will be made sufficiently long to extend into the shank will depend upon the materials and design of the particular model of shoe in which my invention is incorporated. For example, in a lady's shoe having a very light and flexible shank, the strip may extend a considerable distance along the shank, so that its rearward end portion has a secure anchorage therein, whereas in a shoe having a heavier shank, the strip may extend a lesser distance along the shank. In the latter case, the heavier sole affords a better anchorage for the rearward end of the strip. The style or shape of the vamp may also be a factor in determining the length of the strip, since it is the purpose of the strip to hold the sole and the vamp in a slightly stretched condition whenever the shoe is not being worn. For example, in an Oxford type of shoe, the strip would have to be longer than in a sandal type of shoe, because in the former type of shoe the material of the vamp will require a greater force to hold it in shape than the latter type of shoe, and the forces tending to hold the vamp in shape must be applied to the sole throughout a greater length thereof than would be the case with the sandal type. In the sandal type, and in shoes in which the material of the vamp is reduced so as to approach that of the sandal type, the function of the strip is substantially solely to hold the sole straight when the shoe is not being worn. In other types of shoes, more nearly resembling the Oxford type, the strip must not only hold the sole of the shoe straight, but must be of sufficient length and strength to hold the vamp in shape.

While I have shown and described but several of a number of possible embodiments of my invention, I do not wish to be limited to the precise forms shown, but desire to claim all other variations and modifications which may be designed by those skilled in the art to adapt the invention to suit the requirements of particular kinds of shoes and particular manufacturing processes.

What I claim and desire to secure by Letters Patent of the United States, is:

1. In a shoe, a sole structure having secured therein a thin, resilient, metallic strip arcuate upwardly in transverse cross section and extending from a point adjacent to the toe portion of the shoe to the mid portion of the shank, said strip being effective in its undistorted condition to hold the sole and upper of the shoe in its original shape.
2. In a shoe, the combination of a sole, a relatively thin and elastic metallic strip secured to said sole, and extending longitudinally thereof, said strip being arcuate upwardly in transverse cross-section, and lugs formed from said strip and projecting therefrom to anchor said strip against movement relative to said sole.
3. In a shoe, the combination of a sole, and a relatively thin metallic strip embedded in said

sole, said strip being generally arcuate upwardly transversely and being sufficiently elastic that when it is flexed upwardly beyond a critical point it will assume a substantially rectilinear transverse section at the point of flexure and maintain its arcuate shape throughout the remainder of its length. 5

4. In a shoe, the combination of a sole, a relatively thin resilient metallic strip secured to said sole, said strip extending longitudinally of 10 said sole and being arcuate upwardly in transverse cross-section whereby it will offer but little resistance to flexure of said sole when the latter has been flexed upwardly beyond a predetermined extent but will be effective to hold said sole in 15 substantially a plane when the strip is substantially unflexed.

5. In a shoe, the combination of a sole, and means for restraining the toe portion of said sole from bending upwardly with respect to the 20 remaining portion of said sole, said means comprising a thin elastic metallic member arcuate upwardly in transverse cross-section and extending longitudinally of the sole, and means for securing said member to said sole. 25

6. In a shoe, the combination of a sole, and means for restraining the toe portion of said sole from bending upwardly with respect to the remaining portion of said sole, said means comprising a plurality of relatively thin elastic metal- 30 lic strips arcuate upwardly in transverse section extending longitudinally of said sole and secured thereto.

7. In a shoe, the combination of a sole, and means for restraining the toe portion of said 35 sole from bending upwardly with respect to the remaining portion of the sole, said means comprising a relatively thin elastic strip arcuate upwardly in transverse cross section and being slightly longitudinally bowed upwardly in curvature reverse to that of the sole, said strip being structurally incorporated in said sole and extending longitudinally thereof. 40

8. In a shoe, the combination of a sole, and means for restraining the toe portion of said 45 sole from bending upwardly with respect to the remaining portion of said sole, said means comprising a relatively thin elastic metallic strip arcuate upwardly in transverse cross-section em- 50 bedded in said sole, and a pressure distributing member covering said strip.

9. In a shoe, the combination of a sole, and means for restraining the toe portion of said sole from bending upwardly with respect to the remaining portion of said sole when the shoe is not 55 being worn, said means comprising a thin metallic flexible strip arcuate upwardly in transverse cross-section and having a protective coating of an elastic material, said strip being secured to said sole.

10. In a shoe, the combination of a sole, and means for restraining the toe portion of said sole from bending upwardly with respect to the remaining portion of said sole when the shoe is not being worn, said means comprising a thin 65 elastic metallic strip secured to said sole and extending longitudinally thereof, said strip being arcuate upwardly in transverse cross-section and having a tightly adhering rubber coating.

11. In a shoe, the combination of a sole, and means for restraining the toe portion of said sole from bending upwardly with respect to the remaining portion of said sole when the shoe is not being worn, said means comprising a thin 70 elastic metallic strip embedded in said sole and 75

secured against movement relative thereto, said strip being arcuate upwardly in transverse cross-section and slightly bowed upwardly in longitudinal cross-section.

5 12. In a shoe, the combination of a sole, and means capable, at the election of the wearer, of restraining the toe portion of said sole from bending upwardly with respect to the remaining portion of said sole, said means comprising a

thin flexible member arcuate upwardly in transverse cross section except at one place along its length when the shoe is being worn in walking, but arcuate upwardly in transverse section over its entire length after the shoe sole has been pulled downwardly sufficiently to restore said flexible member substantially to its undistorted shape.

ARTHUR O. DAHLBERG.
